(57) **CLAIM**

The ornamental design for a serrated surgical pick, as shown and described,

DESCRIPTION

FIG. 1 is a perspective view of a serrated surgical pick showing my new design;

FIG. 2 is an enlarged fragmentary perspective view of the tip portion thereof;

FIG. 3 is a top plan view thereof;

FIG. 4 is an enlarged fragmentary top plan view of the tip portion thereof;

FIG. 5 is a bottom plan view thereof;

FIG. 6 is an enlarged fragmentary bottom plan view of the tip portion thereof;

FIG. 7 is an enlarged rear elevational view thereof;

FIG. 8 is an enlarged front elevational view thereof;

FIG. 9 is a right side elevational view thereof, the left side elevational view being a mirror image thereof; and,

FIG. 10 is an enlarged fragmentary right side elevational view of the tip portion of FIG. 9, the left side elevational view being a mirror image.
